UNITED STATES PATENT OFFICE

ALBERT B. RYPINSKI, OF LAURELTON, NEW YORK

FOLDING BELT CONVEYER

Application filed November 21, 1930. Serial No. 497,317.

My invention relates broadly to conveyers and more particularly to a construction of foldable portable conveyer.

One of the objects of my invention is to provide a construction of collapsible conveyer comprising a multiplicity of sections which may be folded one upon another for facilitating shipment of the conveyer and to permit storage of the conveyer within a minimum space.

Another object of my invention is to provide a construction of endless belt conveyer having a frame constituted by a multiplicity of foldable sections pivotally connected end to end through which a traveling belt is guided for the advancement of articles from one position to another.

Still another object of my invention is to provide a multiple section frame for an endless belt conveyer wherein the individual sections are pivotally connected end to end with means in each section for maintaining the traveling belt under required tension.

A further object of my invention is to provide a construction of endless belt having means attachable to the driving rollers for positively driving the conveyer.

A still further object of my invention is to provide a construction of self contained multiple section portable conveyer which may be shipped complete in compact folded arrangement ready for use by unfolding the sections, the several sections being disposed in alignment one with another for installation for unskilled labor in any desired location or position.

Another object of my invention is to provide a construction of metallic frame for a multiple section endless belt conveyer wherein each section of the metallic frame is die pressed in an identical manner allowing the sections to be assembled in any desired number of units.

Other and further objects of my invention reside in the construction of multiple section metallic frame for a portable endless belt conveyer as will be more fully set forth in the specification hereinafter following as shown in the accompanying drawings, in which:

Figure 1 is a perspective view of the conveyer set up and in full extended position; Fig. 2 is a side elevation of a portion of the conveyer shown on a large scale; Fig. 3 is a top plan view thereof; Fig. 4 is a central vertical longitudinal sectional view on line 4-4 of Fig. 3; Fig. 5 is a transverse vertical sectional view taken on line 5-5 of Fig. 3, the driving means for the conveyer being preferably an appropriate spring motor as shown in dotted lines; Fig. 6 is a cross sectional view through the driving drum taken on line 6-6 of Fig. 5; Fig. 7 is a transverse vertical sectional view taken on line 7-7 of Fig. 2; Fig. 8 is an end elevation on an enlarged scale looking in the direction of arrows A-A of Fig. 9, the box in which the conveyer may be housed being shown in dotted lines; Fig. 9 is a side elevation of the conveyer folded, the box in which the conveyer may be housed being shown in dotted lines; Fig. 10 is a side elevation of one of the units comprising the various sections of the conveyer detached; Fig. 11 is a side elevation of one of the driving drums of the conveyer; Fig. 12 is a sectional view on line 12-12 of Fig. 11; Fig. 13 is an end elevation thereof; Fig. 14 is a transverse vertical section on line 14-14 of Fig. 11; Fig. 15 is a side elevation of one of the driving pins engaging the flexible conveyer; and Fig. 16 shows a modified form of drive for the endless belt.

The portable conveyer of my invention comprises a plurality of sheet metal sections pivotally connected end to end and adapted to be folded within a compact shipping case for transportation and readily unfolded for use with the several sections aligned one with respect to another. The sectional frame consists of end frames with a multiplicity of intermediate interconnected frames. The end frames each include roller members around which the continuous belt moves. The intermediate frames and the end frames are provided with laterally extending roller members arranged to support the end surface of the traveling belt. The return portion of the endless belt is supported away from the sectional frames by upstruck projections which maintain the belt out of con-

tact with the lower portions of the sectional frames. Each frame section includes a tensioned device adapted to place the endless belt under required tension for maintaining the belt in stretched position and operative over the driving and driven rollers. The driving roller is provided with a plurality of radially positioned pins projecting from the roller and adapted to engage grommets centrally positioned along the belt and through which the pins project during the driving operation of the conveyer. Any suitable motive power may be employed for operating the conveyer. I may provide either a spring motor or an electric motor, or the device may be operated manually. The sheet metal sections forming the frame of the conveyer are identical in construction. That is, all apertures required in each section of the sheet metal frame are accurately punched to receive the required rollers, auxiliary rollers, tensioning means, and interconnecting links as will be more fully hereinafter described. To meet existing conditions, the number of sections of the frame may be varied and the driven and driving rollers mounted in the desired frames. The auxiliary rollers may be journaled in the desired position in the intermediate and end frames for supporting the under surface of the conveyer, and the tensioning means may be readily inserted in each of the sections for stretching the belt in desired manner. The several sections when in collapsed position or folded position occupy relatively small space and enable the conveyer to be readily transported. The belt forming the conveyer is folded in a number of loops corresponding to the number of sections when the multiple section frame is collapsed for shipment or transportation.

Referring to the drawings in more detail, Fig. 1 shows the multiple section frame of the conveyer in extended position supported on the supporting surface 5, the sections being shown at 1, 2, 3 and 4 pivotally interconnected at 6, 7 and 8. Fig. 2 more clearly shows the end frame 1 linked through the pivotal connection 6 with the intermediate frame 2 which is in turn interlinked as indicated at 7 with the intermediate frame 3 which has a pivotal connection with the end frame 4. In order to clearly show the end frame 1, the frames 2, 3 and 4 have been foreshortened. Fig. 3 illustrates in plan view the arrangement of the endless belt 10 with respect to the several frames.

Each section is pressed from sheet metal and is identical in its construction. Perforations are made in the metallic material constituting each section during the die pressing operation so that the sections are interchangeable. Section 1 provides a journal adjacent one end thereof for shaft member 14 which is rotatably mounted between the

upstanding side walls of section 1 as illustrated in Fig. 5. The shaft 14 is provided with sleeves 14a at each end thereof spacing the drive roller 12 away from the interior side walls. The shaft 14 is extended at one side 70 and is provided with a pin 18 extending therethrough providing coupling means to which the drive motor 19 may be connected. The motor 19 may be a spring wound device or an electric motor may be employed which is coupled to any suitable means indicated at 20 with pin 18 in shaft 14. In order to insure a positive drive between drive roller 12 which is secured on driven shaft 14 and belt 10, I provide radially disposed sockets 15 in roller 80 12 which receive oppositely directed pins 16. The pins 16 are provided with heads 16a which project through apertures in grommets 11 disposed along the center line of belt 10 and spaced at intervals corresponding to the 85 peripheral distance around roller 12 between the heads 16a and pins 16. As roller 12 is driven the heads 16a grip the belt 10 by projecting through the apertures in grommets 11 and positively driving the belt. In order 90 to center the belt with respect to the frame of the conveyer the parallel extending upper extremities of each section are turned downwardly as represented at 1a and 1b and project downwardly for a distance substantially 95 beneath the plane of the belt 10. The in-turned edge portions 1a and 1b serve to center articles upon the belt enabling the articles to be advanced as the belt is driven without being dislodged from the conveyer. In 100 order to support the load on the conveyer, I provide a multiplicity of auxiliary rollers indicated 21 which are journaled at their opposite ends in the depending side portions 1a and 1b and are spaced at intervals along 105 the several sections of the frame to support the under surface of belt 10 intermediate the driving and driven rollers. These auxiliary rollers are provided in the intermediate sections 2 and 3 and in the end sections 1 and 4 110 as shown. In the extremity of end section 4 I provide means for journaling the shaft 22 which carries the driven roller 23 around which the belt 10 passes in changing its direction for return to the driving roller 12. The driven roller 23 is centrally grooved at 24 in a manner similar to the groove 17 in driving roller 12 in order to permit the grommets 11 to pass freely therearound without dislodging the belt from position. In order to limit 115 the catenary effect of the belt and prevent undue dragging of the belt upon the bottom of the several sections of the frame, I provide upstruck projections 25 in the bottom of the sheet metal sections thereby elevating 120 the belt off of the bottom of the frame sections. Similar projections are provided in the sheet metal frame sections but directed downwardly as indicated at 26 for supporting the frame sections as shown. The belt in 125

each frame section is subject to slack and in order to maintain the required tension I provide an adjustable tension device for each section as shown particularly in Figs. 4 and 7. 5 A pair of arms 27 are pivoted at 28 in the side walls of each section of the conveyer. The arms 27 are free to be moved angularly through a limited arc determined by the length of the slots 29 from the opposite side walls of the conveyer sections. Adjustable screws 30 pass through the slots 29, enabling the arms to be fixed in selected position with respect to the side walls of the frame. A roller 31 is journaled in the ends of arms 15 27 and is adapted to engage the under surface of the lower side of belt 10 in order to support the same. By adjusting the angular position of arms 27 by loosening screws 30 and again tightening the same, the roller 31 may be moved into that position required for maintaining the belt under sufficient tension. 20

Figures 8 and 9 show the collapsed position of the several sections. The sections are folded one upon another as shown. To 25 permit this foldable arrangement the sections are pivotally connected end to end but in opposite corners. That is, section 1 is hinged to section 2 by links pivotally connected at 6 whereas section 2 is hinged to section 3 at 7 in the opposite corners of the intermediate frames 2 and 3. Again at the opposite corner a linkage is provided between intermediate frame 3 and frame 4 as shown at 8. It 30 will be observed that all of the frames are apertured in a similar manner as heretofore noted and it will likewise be observed that all of the apertures thus provided are not used in each of the frames. However by 35 providing the several apertures the frames 40 may be connected in any desired arrangement without repunching or redrilling additional apertures. In folded position the belt 10 assumes the dotted line arrangement shown in Fig. 9 where the loops of the belt 45 fold in a substantially serpentine arrangement. Figure 8 shows that the upper face of sections 1 and 2 are collapsed. The lower face of sections 2 and 3 collapse adjacent each other with the upper faces of sections 50 3 and 4 adjacent each other. In this way the belt is fully protected and the sections are readily unfolded when placing the conveyer in operation. The packing case for 55 the conveyer has been shown at 33, illustrating the compactness with which the endless belt conveyer is capable of being transported.

In lieu of the pin drive arrangement I may 60 employ the modified arrangement of drive roller shown in Fig. 16 wherein a roller 34 is carried by shaft 14 over which a rubber sleeve 35 is cemented. The rubber sleeve 35 has a frictional surface indicated by the 65 corrugations 36 which grip the belt 10 and

impart sufficient tractive force thereto to drive the belt without lost motion.

The conveyer of my invention is particularly adapted for operation as a means for loading cars, ships, or for the transporting of articles from one place to another under many varieties of conditions. It requires no great degree of skill to unfold and set up the conveyer of my invention. The conveyer may be changed around from one location to another after installation and the direction of movement of the material which is transported may accordingly be controlled. The conveyer of my invention may be constructed in various sizes from a miniature toy conveyer to a large size heavy duty conveyer for moving relatively bulky loads. 70 75 80 85

While I have described my invention in certain preferred embodiments I desire that it be understood that modifications may be made and that no limitations upon my invention are intended other than are imposed by the scope of the appended claims. 90

What I claim as new and desire to secure by Letters Patent of the United States is as follows:

1. An endless belt conveyer comprising a multiplicity of separate frame sections pivotally connected end to end, each of said frame sections including upwardly projecting side portions terminating in downwardly extending edge portions, said sections including end frames and interconnected intermediate frames, a driving roller journaled in the end of one of said end frames, a driven roller journaled in the end of the other of said end frames, auxiliary rollers journaled in the downwardly extending edge portions of said frame sections, and a belt looped over said driving and driven rollers and extending over said auxiliary rollers for conveying material longitudinally of said frame sections. 100 105

2. An endless belt conveyer comprising a multiplicity of separate frame sections pivotally connected end to end, each of said frame sections including upwardly projecting side portions terminating in downwardly extending edge portions, said sections including end frames and interconnected intermediate frames, a driving roller journaled in the end of one of said end frames, a driven roller journaled in the end of the other of said end frames, auxiliary rollers journaled in the downwardly extending edge portions of said frame sections, and means carried by each 110 115 120 of said frame members for subjecting said belt to tension.

3. An endless belt conveyer comprising a multiplicity of separate frame sections pivotally connected end to end, each of said frame sections including upwardly projecting side portions having their edges rolled inwardly and downwardly, said sections including end frames and interconnected intermediate frames, a driving roller journaled in the side 125 130

portions of one of said end frames adjacent one end thereof, a driven roller journaled in the side portions of the other of said end frames adjacent the opposite end thereof,
5 auxiliary rollers journaled in the downwardly directed edge portions of said frame sections, a belt threaded over said driving and driven rollers and supported by said auxiliary rollers, and means disposed centrally
10 of each of said frame sections and extending between said side portions thereof for subjecting said belt to tension.

4. An endless belt conveyer comprising a multiplicity of separate frame sections pivotally connected end to end, each of said frame sections including upwardly projecting side portions terminating in downwardly extending edge portions, said sections including end frames and interconnected intermediate frames, a driving roller journaled in the end of one of said end frames, a driven roller journaled in the end of the other of said end frames, auxiliary rollers journaled in the downwardly extending edge portions
20 of said frame sections, and an adjustably positioned roller journaled in each of said frame members and operative against said belt for subjecting said belt to tension.

In testimony whereof I affix my signature.

30 ALBERT B. RYPINSKI.
